UNITED STATES PATENT OFFICE

2,067,792

CIRCUIT BREAKER

Joseph W. Seaman, Upper Darby, Pa., assignor
to General Electric Company, a corporation of
New York

Application May 6, 1936, Serial No. 78,179

16 Claims. (Cl. 200—109)

My invention relates to circuit breakers, more particularly to circuit breakers of the type provided with manual mechanism for operating the circuit controlling contacts between open and closed circuit positions and with automatic tripping means for operating the contacts to open circuit position upon the occurrence of predetermined current conditions, and has for an object the provision of a simple and inexpensive trip device for circuit breakers of this type which is reliable and positive in its operation.

Circuit breakers of the above type have recently found considerable industrial application in connection with which a high degree of reliability is imperative. For example, a circuit breaker, in order to be entirely satisfactory, must always operate automatically to interrupt the circuit in response to predetermined current conditions and must never operate accidentally to interrupt the circuit. In many cases, it is found necessary to mount the circuit breaker on a support which is subjected to recurrent jars or shocks. For example, circuit breakers applied to the control of the various electrical circuits on a naval vessel, such as a battleship or a destroyer, are subjected to shocks of considerable magnitude each time a gun is fired, and it will be obvious that accidental tripping of a circuit breaker upon the occurrence of such a shock would be highly unsatisfactory.

While various types of trip devices have heretofore been employed, many of which are to a large extent satisfactory, much is yet to be desired in a trip device for a circuit breaker of this type, which trip device is extremely sensitive and which is substantially unaffected by shocks or jars imparted to the base of the circuit breaker. Accordingly, it is a further object of my invention to provide a trip device of this character which is extremely sensitive in its operation and which is substantially shockproof.

In carrying out my invention in one form, I provide a trip device for a circuit breaker having a tripping member biased for movement to a tripping position, which trip device comprises a pivoted latching member having an elongate cam slot into which a portion of the tripping member extends. The cam slot is provided with a shoulder adapted to be engaged by an extending portion of the tripping member when the latching member is in its latching position, and with an elongate portion along which the extending portion of the tripping member moves upon movement of the latching member to its releasing position. Normally, the latching member is re-

strained in latching position by a statically balanced trip shaft, the position of which is substantially unaffected by shocks or jars, and means are provided for rotating the trip shaft to release the latching member.

More specifically, the extending portion of the tripping member comprises a roller which exerts on the engaging shoulder in the cam slot a force tending to move the latching member to releasing position, the relation of the shoulder and the roller being such that only a small component of the total force exerted by the roller is exerted in a direction to move the latching member about its pivot. The rotatable trip shaft is provided with a transverse notch through which the end of the latching member moves when the shaft is rotated to a predetermined position, and with a transversely extending operating arm, the shaft being journaled for rotation on an axis passing substantially through the center of gravity of the shaft and the operating arm.

For a more complete understanding of my invention, reference should now be had to the drawings, in which Fig. 1 is a plan view of a circuit breaker provided with a trip device embodying my invention, the cover of the circuit breaker being removed to show the operating mechanism; Fig. 2 is an elevational view, partly in section, of the circuit breaker shown in Fig. 1; Fig. 3 is an end view of the circuit breaker; Fig. 4 is a fragmentary, sectional view taken along the line 4—4 of Fig. 3; Fig. 5 is a similar sectional view, showing the trip device in another of its operating positions; and Fig. 6 is a detail view of the shock-proof, electromagnetic means provided for operating my improved trip device.

Referring now to the drawings, I have shown my invention in one form as embodied in a trip device 10 which is applied to a three-pole circuit breaker of the type described and claimed in a copending application of Winfield A. Atwood, Serial No. 29,479, filed July 2, 1935, entitled "Circuit breakers", which application is assigned to the same assignee as the present invention.

As described in the said Atwood application, the circuit breaker comprises a plurality of individual single-pole units 11, 12, and 13, respectively, the bases of which are rigidly secured together in side-by-side relation, with suitable insulating barriers 14 and 15 interposed therebetween. The single-pole units 11, 12, and 13 are identical in construction, and accordingly, only the single-pole unit 11 will be described in detail. As shown best in Fig. 2, this single-pole unit 11 comprises a base member 16, preferably

formed of insulating material and provided with a housing 17 within which is located a circuit interrupter 18 of the compression chamber type, having a fixed contact 19 and a movable contact 20.

Secured to the base 16 adjacent the housing 17, is a U-shaped frame 21 which supports the operating mechanism. For the purposes of the present invention, this operating mechanism 10 may be briefly described as comprising a pair of overcenter springs 22, the respective adjacent ends of which are connected to the opposite ends of a pin 23 which extend through a slot (not shown) in the extending end of the movable contact 20, the other ends of the springs 22 being connected to a pin 24 which is supported on the free ends of a pair of levers 25, the opposite ends of which are pivotally mounted on a fixed pin 26. The pin 24 extends through a slot (not shown) in an operating member 27 which is pivotally mounted on a pin 28 supported by the frame 21.

Also pivoted on the pin 28 is a tripping member 29 which is normally held in the position shown in Figs. 1 to 4 against the bias of a tripping spring 30 by my improved trip device 10 in a manner to be more fully described later. This tripping member 29 is provided with an extending finger 31 (Figs. 4 and 5) arranged 30 to engage a crosswise extending portion 32 of a guide link 33, one end of which is pivotally supported on the pin 28, and the other end of which pivotally engages the pin 23.

As stated above, the single-pole units 11, 12, 35 and 13 are identical in construction and, as shown, the operating member 27 of the unit 12 is provided with an insulated handle 34, the operating members 27 of the three single-pole units being connected together by means of an 40 insulated crossbar 35. It will be apparent now that when the handle 34 is moved to rotate the operating member 27 of the single-pole unit 12 about its pivot, the crossbar 35 will effect rotation of the operating members 27 of the units 11 and 13 so as to carry the springs 22 of the three units overcenter relative to the respective pivot pins 28. Accordingly, the movable contacts 20 of the three units will be simultaneously operated between open and closed circuit positions with a snap action, as is more fully described in the above referred to Atwood application.

A second insulated crossbar 36 which likewise extends across the three single-pole units is connected to the tripping members 29 and is provided with an extending finger 37. Thus, it will be seen that the finger 37, together with the cross bar 36 and the tripping members 29, constitutes a tripping member for the circuit breaker which is biased to tripping position by the springs 30, the position of this tripping member being controlled by my improved trip device in the manner now to be described.

As shown best in Figs. 1 and 3, my improved trip device 10 is supported on a U-shaped frame which comprises a pair of spaced apart plates 38 and 39 secured to the base 16 of the center unit 12, the upwardly extending ends of the plates 38 and 39 rotatably supporting a balanced trip shaft 40. This trip shaft 40 is provided intermediate the plates 38 and 39 with a transversely extending arm or trip paddle 41, and the ends of the shaft which extend outwardly over the units 11 and 13 carry transversely extending paddles or arms 42 and 43,

preferably formed of insulating material. Adjacent the arm 41, a portion of the trip shaft 40 is cut away to provide a transversely extending notch 44.

Arranged for co-operation with the trip shaft 40, I provide a latching member 45 which is pivotally mounted on a pin 46 carried by an extending portion of the plate 39 (Figs. 4 and 5), the free end of the latching member 45 comprising a latching tip 47. As shown, the latching member 45 is in alignment with the notch 44, and accordingly, the latch tip 47, which normally engages the periphery of the shaft 40, as shown in Fig. 4, is movable through the notch 44 to the releasing position shown in Fig. 5 when the shaft 40 is rotated to the position there shown. Intermediate its ends, the latch member 45 is provided with an elongate cam slot 48 into which extends a roller 49 carried by the finger 37, which finger, as described above, constitutes a portion of the tripping member for the circuit breaker.

As shown, the cam slot 48 is provided with a shoulder 50 adapted to be engaged by the roller 49 when the latching member 45 is in its latching position, shown in Fig. 4, and an elongate portion 51 along which the roller 49 moves as the latching member 45 moves to the releasing position shown in Fig. 5. Likewise, the cam slot 48 is provided with a resetting portion or 30 shoulder 52, the function of which will be more fully described hereinafter.

It will be apparent that in the latching position shown in Fig. 4, the roller 49 exerts a force on the shoulder 50 tending to rotate the latching member 45 to the releasing position shown in Fig. 5. The shoulder 50, however, is arranged at such an angle relative to the path of movement of the roller 49 and to the pivot 46 that the greater portion of the force exerted on the shoulder 50 is absorbed by the pivot pin 46, only a small component of the total force being in a direction to rotate the latch member 45. Furthermore, it will be seen that the force exerted on the shaft 40 by the latch tip 47 constitutes only a fraction of the rotative component exerted on the shoulder 50, since the latch tip 47 is at a greater distance from the pivot pin 46 than is the shoulder 50. Because of the relatively light load imposed on the shaft 40 by the latch tip 47, a high degree of sensitivity is obtained, while providing positive latching of the finger 37.

In order that the trip device 10 shall be substantially shockproof, the shaft 40, which constitutes the primary latching member, must be substantially unaffected by shocks imparted to the circuit breaker base. Since the pivot pin 46 and the portion of the shaft 40 adjacent the notch 44 are supported on the same supporting plate 39, it will be apparent that no lateral displacement of the shaft relative to the latching member 45 will be caused by shocks or jars imparted to the circuit breaker base, and in order that such shocks may not cause rotation of the shaft 40, I construct the shaft 40 and the arms 41, 42, and 43 as a statically balanced unit journaled in the plates 38 and 39, for rotation about a longitudinal axis passing substantially through the center of gravity of the balanced unit. It will of course be understood that perfect static balance is rather difficult to obtain, and accordingly, shocks of very great magnitude may cause a slight rotation of the shaft 40. In order that a series of such excessive shocks may not cause 7

a gradual step-by-step movement of the shaft 40 to its releasing position, I provide a resetting spring 53 (Figs. 1 and 3), which is effective automatically to return the shaft 40 to its fully latched position, following any slight rotational movement thereof due to such shocks.

Although the latching member 45 and the shaft 40 may be arranged in any desired manner so that rotation of the shaft releases the latch tip 47 for movement through the notch 44, I have shown for purposes of illustration a preferred arrangement which is specifically described and claimed in the copending application of Robert W. Smith, Serial No. 78,177, filed May 6, 1936, entitled "Circuit breakers", which application is assigned to the same assignee as the present invention. As described in the said Smith application, the pivot pin 46 and the trip shaft 40 are so arranged that the latch tip 47 moves along an arc passing substantially through the center of the shaft 40, the notch 44 being cut back slightly past the center of the shaft so as to permit movement of the latch tip 47 along the said arc when the shaft is rotated to its releasing position. Thus, the latch tip 47 engages the periphery of the shaft 40 substantially tangentially, and the force exerted thereby on the shaft 40 is along a substantially radial line so that no rotative movement is exerted on the shaft 40 by the latch tip 47. Consequently, in order to rotate the shaft 40 to its releasing position, only the force of the spring 53 and the slight frictional force between the latch tip 47 and the shaft 40 need be overcome.

While any suitable current responsive means, either thermal or magnetic, may be provided for engaging one or more of the arms 41, 42, and 43 to rotate the trip shaft 40, I have shown associated with each pole of the circuit breaker, shockproof electromagnetic means of the type described and claimed in the above referred to Smith application.

As shown best in Fig. 6, each electromagnetic device comprises a magnetizable core 54 provided with pole pieces 55 and 56, the pole piece 55 being mounted on a support 57 secured to the base of the circuit breaker, the support 57 for the pole unit 12 being formed integrally with the supporting plate 38. The pole piece 56 for each of the electromagnetic devices is bifurcated, as shown best in Fig. 3, and is provided with a pivot pin 58 (Fig. 6) on which is mounted a magnetizable armature 59, the upwardly extending end of which carries an adjustable member 60 to which is attached one end of a biasing spring 61, the other end of the spring 61 being connected to a support 62 (Fig. 2) formed of insulating material extending outwardly from a terminal screw 63. As is more fully explained in the above Smith application, the armature 59 is pivoted about its center of gravity so as to be substantially unaffected by shocks transmitted through the pivot pin 58, and is provided with a shock spring 64, one end of which is secured to the armature by a screw 65 and the other end of which is maintained under tension closely adjacent the lower end of the armature by a stop screw 66. As shown, the biasing spring 61 tends to rotate the armature 59 away from the pole piece 55 and toward a fixed stop 67 which is formed integrally with the support 57. The shock spring 64, however, is arranged to engage the stop 67 to hold the armature out of direct engagement therewith so as to prevent the transmission of shocks from

the stop 67 to the armature 59. Extending outwardly from each of the armatures 59, is an adjustable screw 68 arranged to engage the associated one of the arms 41, 42, and 43 to rotate the trip shaft 40 when the armature 59 is attracted from the biased position shown in Fig. 6 upon energization of a winding 69 which surrounds the core 54.

One end of the energizing winding 69, as shown best in Fig. 2, is connected to the terminal screw 63, which, in turn, is connected by a conductor 70 to an external terminal 71, and the other end of the winding 69 is connected (Fig. 6) to a flexible conductor 72 leading to the associated movable contact 20. Thus, the circuit through each pole of the circuit breaker may be traced (Fig. 2) from the terminal screw 71 through the conductor 70, the terminal screw 63, the winding 69, the flexible conductor 72, the fixed contact 20, the movable contact 19, and by way of a conducting strap 73 to another external terminal 74.

It is now believed that a complete understanding of my invention may be had from a description of the operation. In Figs. 1 to 4, inclusive, the circuit breaker is shown in its closed circuit position, and it will be assumed that an overload occurs in the center pole unit 12 of sufficient magnitude to energize the associated winding 69 so as to attract the lower end 30 of the armature 59 from the biased position shown best in Figs. 2, 4, and 6, to the attracted position shown in Fig. 5. As the armature moves to this position, the screw 68 carried by the armature 59 engages the trip arm 41 and rotates the shaft 40 to the releasing position shown in Fig. 5, whereupon the force exerted by the roller 49 on the shoulder 50 rotates the latch member 45 to the releasing position shown in Fig. 5, the latch tip 47 moving through the slot 44 and the roller 49 moving upwardly along the portion 51 of the cam slot 48. It will be understood of course that as the finger 37 and the insulated crossbar 36 are moved to the position shown in Fig. 5, the tripping members 29 associated with each pole of the circuit breaker are rotated in a clockwise direction about the pivot pin 28, and the extending finger 31 on each of these tripping members engages the cross portion 32 to operate the links 33 and the movable contacts 20 to the open circuit position shown in Fig. 5.

As the movable contacts 20 move to the open circuit position, it will be seen that the lower end of each overcenter spring 22 is carried over-center relative to the pivot pin 26, and accordingly, the force exerted by the springs on the links 25 is reversed, and the upper ends of these links are thereupon rotated in a counterclockwise direction to move the operating members 27, the insulated crossbar 35, and the operating handle 34 to the midposition shown in Fig. 5, in which position the operating handle 34 engages the insulated crossbar 36.

It will be understood of course that as soon as the circuit breaker is operated to its open circuit position, the energizing windings 69 on all of the current responsive devices will be de-energized, and accordingly, the armatures 59 will be returned to their biased positions by the springs 61. Thus, the trip shaft 40 is released for rotation in a counterclockwise direction to its latching position under the force exerted by the resetting spring 53. The shaft 40 will be restrained against such rotation, however, so

long as the latching member 45 is in the position shown in Fig. 5 by engagement of the latch tip 47 with the base of the slot 44. In order to reset the tripping mechanism, therefore, it is necessary to return the latching member 45 to the position shown in Fig. 4, and this may be accomplished simply by rotating the operating handle 34 in a counterclockwise direction from the position shown in Fig. 5 so as to press downwardly on the crossbar 36 and rotate the tripping member, which includes the finger 37, in a counterclockwise direction about the pivot pin 28.

As the crossbar 36 and the finger 37 are moved in this direction, it will be seen that the roller 49 moves along the portion 51 of the cam slot 48 until it engages the resetting shoulder 52, whereupon a cam action is exerted on the shoulder 52 tending to rotate the latch member 45 in a counterclockwise direction from the position shown in Fig. 5, the roller 49 in its extreme position engaging the tip of the resetting portion 52. As soon as the latch tip 47 moves out of the slot 44, the resetting spring 53 rotates the trip shaft 40 to the position shown in Fig. 4 and upon release of the operating handle 34, the tripping springs 38 will tend to rotate the latch finger 37 in a clockwise direction about the pivot 28. Movement of the latch finger 37 in this direction, however, is prevented by engagement of the roller 49 with the shoulder 50, and clockwise rotation of the latching member 45 under the force exerted on the shoulder 50 will be prevented by engagement of the latching tip 47 with the periphery of the trip shaft 40. Accordingly, the trip device will assume the latched position shown in Fig. 4, and the circuit breaker may thereafter be closed simply by rotating the operating handle 34 in a clockwise direction to the position shown in Fig. 4.

While I have shown a particular embodiment of my invention, it will be understood, of course, that I do not wish to be limited thereto, since modifications may be made and I, therefore, contemplate by the appended claims to cover any such modifications as fall within the true spirit and scope of my invention.

What I claim as new and desire to secure by Letters Patent of the United States is:

50 1. A trip device for a circuit breaker having a tripping member biased for movement to a tripping position, said trip device comprising a pivoted latch member movable between latching and releasing positions having a cam slot into which a latching portion of said tripping member extends, said cam slot including a shoulder engageable by said latching portion to restrain said tripping member against movement to said tripping position when said latch member is in said latching position and an elongate portion along which said latching portion moves to said tripping position when said latch member is moved to said releasing position, said latching portion exerting a force on said shoulder tending to move said latch member to said releasing position, and current responsive means normally restraining said latch member in said latching position for releasing said latch member for movement to said releasing position, whereupon said tripping member moves to said tripping position.

2. A trip device for a circuit breaker having a tripping member biased for movement to a tripping position, said trip device comprising a pivoted latch member movable between latching and releasing positions having a cam slot into which

a latching portion of said tripping member extends, said cam slot including a shoulder engageable by said latching portion to restrain said tripping member against movement to said tripping position when said latch member is in said latching position and an elongate portion along which said latching portion moves to said tripping position when said latch member is moved to said releasing position, said latching portion exerting a force on said shoulder tending to move said latch member to said releasing position, and current responsive means normally restraining said latch member in said latching position for releasing said latch member for movement to said tripping position, whereupon said tripping member moves to said tripping position, said cam slot including a resetting portion engageable by said latching portion of said tripping member upon return movement of said tripping member for returning said latch member to said latching position.

3. A trip device for a circuit breaker having a tripping member biased for movement to a tripping position, said trip device comprising a latching roller carried by said tripping member, a pivoted latch member movable between latching and releasing positions having an elongate cam slot into which said roller extends, said cam slot including a shoulder engageable by said roller to restrain said tripping member against movement when said latch member is in said latching position and a portion along which said roller moves to said tripping position when said latch member is moved to said releasing position, said roller when engaging said shoulder exerting a force tending to move said latch member to said releasing position, and current responsive means normally restraining said latch member in said latching position for releasing said latch member for movement to said releasing position, whereupon said tripping member is released for movement to said tripping position.

4. A trip device for a circuit breaker having a tripping member biased for movement to a tripping position, said trip device comprising a latching roller carried by said tripping member, a pivoted latch member movable between latching and releasing positions having an elongate cam slot into which said roller extends, said cam slot including a shoulder engageable by said roller to restrain said tripping member against movement when said latch member is in said latching position and a portion along which said roller moves to said tripping position when said latch member is moved to said releasing position, said roller when engaging said shoulder exerting a force tending to move said latch member to said releasing position, and current responsive means normally restraining said latch member in said latching position for releasing said latch member for movement to said releasing position, whereupon said tripping member is released for movement to said tripping position.

5. A trip device for a circuit breaker having a tripping member biased for movement to a tripping position, said trip device comprising a latching roller carried by said tripping member, a pivoted latch member movable between latching and releasing positions having an elongate cam slot into which said roller extends, said cam slot including a shoulder engageable by said roller

to restrain said tripping member against movement to said tripping position when said latch member is in said latching position and a portion along which said roller moves to said tripping position when said latch member is moved to said releasing position, said roller exerting a force on said shoulder tending to move said latch member to said releasing position, and current responsive means normally restraining 5 said latch member in said latching position for releasing said latch member for movement to said releasing position, whereupon said tripping member moves to said tripping position, said cam slot including a portion engageable by said 10 roller upon return movement of said tripping member for returning said latch member to said latching position.

6. A trip device for a circuit breaker having a tripping member biased for movement to a tripping position, said trip device comprising a latch member, means pivotally mounting said latch member for movement between latching and releasing positions, current responsive means normally engaging an end of said latch 25 member remote from said pivot means for restraining said latch member in said latching position, said latch member having an elongate cam slot intermediate said pivot means and said remote end into which a latching portion of 30 said tripping member extends, said cam slot including a shoulder engageable by said latching portion for restraining said tripping member against movement to said tripping position when said latch member is in said latching position 35 and an elongate portion along which said latching portion moves to said tripping position when said latch member is moved to said releasing position, said latching portion exerting a force on said shoulder tending to move said latch 40 member to said releasing position and said current responsive means upon the occurrence of predetermined current conditions releasing said latch member for movement to said releasing position, whereupon said tripping member moves 45 to said tripping position.

7. A trip device for a circuit breaker having a tripping member biased for movement to a tripping position, said trip device comprising a latching roller carried by said tripping member, 50 a latch member, means pivotally mounting said latch member for movement between latching and releasing positions, current responsive means normally engaging an end of said latch member remote from said pivot means for restraining 55 said latch member in said latching position, said latch member having an elongate cam slot intermediate said pivot means and said remote end into which said latching roller extends, said cam slot including a shoulder engageable by 60 said roller for restraining said tripping member against movement to said tripping position when said latch member is in said latching position and a portion along which said roller moves to said tripping position when said latch member 65 is moved to said releasing position, said roller exerting a force on said shoulder tending to move said latch member to said releasing position and said current responsive means upon the occurrence of predetermined current conditions 70 releasing said latch member for movement to said releasing position, whereupon said tripping member moves to said tripping position, and resetting means including a portion of said cam slot engageable by said roller upon return, movement of said tripping member from said 75

tripping position for returning said latch member to said latching position.

8. A trip device for a circuit breaker having a tripping member biased for movement to a tripping position, said trip device comprising a 5 pivoted latch member movable between latching and releasing positions having a cam slot into which a latching portion of said tripping member extends, said cam slot including a shoulder engageable by said latching portion to restrain 10 said tripping member against movement to said tripping position when said latch member is in said latching position and an elongate portion along which said latching portion moves to said tripping position when said latch member is 15 moved to said releasing position, said latching portion exerting a force on said shoulder tending to move said latch member to said releasing position, shockproof, releasable restraining means for said latch member including a rotatable 20 shaft having a transversely extending notch therein and a transversely extending operating arm, means mounting said shaft for rotation about an axis passing through the center of gravity of said shaft and said operating arm 25 whereby substantially no rotative movement of said shaft is produced by shocks imparted to said mounting means, a portion of said shaft adjacent said notch normally engaging said latch member to restrain said latch member in said 30 latching position, and current responsive means for engaging said operating arm to rotate said shaft to a position in which said latch member is released for movement through said notch, whereupon said tripping member is released for 35 movement to said tripping position.

9. A trip device for a circuit breaker having a tripping member biased for movement to a tripping position, said trip device comprising a latching roller carried by said tripping member, 40 a pivoted latch member movable between latching and releasing positions having an elongate cam slot into which said roller extends, said cam slot including a shoulder engageable by said roller to restrain said tripping member against 45 movement when said latch member is in said latching position and a portion along which said roller moves to said tripping position when said latch member is moved to said releasing position, said roller when engaging said shoulder exerting 50 a force tending to move said latch member to said releasing position, shockproof, releasable restraining means for said latch member including a rotatable shaft having a transversely extending notch therein and a transversely extending operating arm, means mounting said shaft for rotation about an axis passing through the center of gravity of said shaft and said operating arm whereby substantially no rotative movement 55 of said shaft is produced by shocks imparted to said mounting means, a portion of said shaft adjacent said notch normally engaging said latch member to restrain said latch member in said latching position, and current responsive means for engaging said operating arm to rotate said shaft to a position in which said latch member is released for movement through said notch, whereupon said tripping member is released for 60 movement to said tripping position.

10. A trip device for a circuit breaker having 70 a tripping member biased for movement to a tripping position, said trip device comprising a latching roller carried by said tripping member, a pivoted latch member movable between latching and releasing positions having an elongate 75

cam slot into which said roller extends, said cam slot including a shoulder engageable by said roller to restrain said tripping member against movement when said latch member is in said 5 latching position and a portion along which said roller moves to said tripping position when said latch member is moved to said releasing position, said roller when engaging said shoulder exerting a force tending to move said latch member to said releasing position, shockproof, releasable restraining means for said latch member including a rotatable shaft having a transversely extending notch therein and transversely extending operating arm, means mounting said 10 shaft for rotation about an axis passing through the center of gravity of said shaft and said operating arm whereby substantially no rotative movement of said shaft is produced by shocks imparted to said mounting means, means biasing said shaft to one position in which a portion of said shaft adjacent said notch engages said latch member to restrain said latch member in said latching position, and current responsive means for engaging said operating arm to rotate said shaft to a second position in which said latch member is released for movement through said notch to release said tripping member.

11. A trip device for a circuit breaker having a tripping member biased for movement to a tripping position, said trip device comprising a latching roller carried by said tripping member, a pivoted latch member movable between latching and releasing positions having an elongate cam slot into which said roller extends, said cam slot including a shoulder engageable by said roller to restrain said tripping member against movement when said latch member is in said latching position and a portion along which said roller moves to said tripping position when said latch member is moved to said releasing position, said roller when engaging said shoulder exerting a force tending to move said latch member to said releasing position, shockproof, releasable restraining means including a statically balanced rotatable shaft having a transversely extending notch therein and a transversely extending operating arm, means biasing said shaft to one position in which said latch member is restrained in said latching position by a portion of said shaft adjacent said notch, and current responsive means for actuating said operating arm to rotate said shaft to a second position whereby said latch member is released for movement through said notch to release said tripping member.

12. A trip device for a circuit breaker comprising a latch member movable between latching and releasing position and shockproof, releasable restraining means for said latch member including a rotatable shaft having a transversely extending notch therein and a transversely extending operating arm, means mounting said shaft for rotation about an axis passing through the center of gravity of said shaft and said operating arm whereby substantially no rotative movement of said shaft is produced by shocks imparted to said mounting means, a portion of said shaft adjacent said notch normally engaging said latch member to restrain said latch member in latching position, and current responsive means for engaging said operating arm to rotate said shaft to a position in which said latch member is released for movement through said notch to said releasing position.

13. A trip device for a circuit breaker comprising a latch member movable between latching and releasing position and shockproof, releasable restraining means for said latch member including a rotatable shaft having a transversely extending notch therein and a transversely extending operating arm, means mounting said shaft for rotation about an axis passing through the center of gravity of said shaft and said operating arm whereby substantially no rotative movement of said shaft is produced by shocks imparted to said mounting means, means biasing said shaft to one position in which a portion of said shaft adjacent said notch engages said latch member to restrain said latch member in said latching position, and current responsive means for engaging said operating arm to rotate said shaft to a second position in which said latch member is released for movement through said notch to said releasing position.

14. A trip device for a circuit breaker comprising a latch member movable between latching and releasing positions, a support on which said latch member is pivoted for movement, and shockproof, releasable restraining means for said latch member including a rotatable shaft having a transversely extending notch therein and a transversely extending operating arm, said shaft being journaled in said support for rotation about an axis passing through the center of gravity of said shaft and said operating arm whereby substantially no rotative movement of said shaft is produced by shocks imparted to said support, means biasing said shaft to one position in which said latch member is restrained in said latching position by a portion of said shaft adjacent said notch, and current responsive means for engaging said operating arm to rotate said shaft to a second position in which said latch member is released for movement through said notch to said releasing position.

15. A trip device for a multipole circuit breaker comprising a latch member movable between latching and releasing positions, shockproof, releasable restraining means for said latch member including a shaft extending across at least two of the poles of said circuit breaker and having a transversely extending notch therein, a plurality of transversely extending operating arms for said shaft, means mounting said shaft for rotation about an axis passing through the center of gravity of said shaft and said operating arms whereby substantially no rotative movement of said shaft is produced by shocks imparted to said mounting means, means biasing said shaft to one position in which said latch member is restrained in said latching position by a portion of said shaft adjacent said notch, and current responsive means associated with at least two poles of said circuit breaker for actuating said operating arms to rotate said shaft to a second position in which said latch member is released for movement through said notch to said releasing position.

16. A trip device for a multipole circuit breaker having a tripping member biased for movement to a tripping position, said trip device comprising a latching roller carried by said tripping member, a supporting frame, a latch member pivotally mounted on said frame for movement between latching and releasing positions, said latch member having an elongate cam slot into which said latching roller extends, said cam slot including a shoulder engageable by said roller

to restrain said tripping member against movement to said tripping position when said latch member is in said latching position and a portion along which said roller moves to said tripping position when said latch member is moved to releasing position, said roller when engaging said shoulder exerting a force tending to move said latch member to said releasing position, shockproof, releaseable restraining means for said latch member including a shaft extending across at least two poles of said circuit breaker and having a transversely extending notch therein, a plurality of transversely extending operating arms on said shaft, said shaft being journaled in said supporting frame for rotation

about an axis passing through the center of gravity of said shaft and said operating arms whereby substantially no rotative movement of said shaft is produced by shocks imparted to said frame, means biasing said shaft to one position in which said latch member is restrained in said latching position by a portion of said shaft adjacent said notch, and a plurality of current responsive devices individually associated with at least two poles of said circuit breaker for actuating said operating arms to rotate said shaft to a second position in which said latch member is released for movement through said notch to release said tripping member.
